RAILROAD BASE PLATE AND FASTENER

Wesley E. Wenner, Allentown, Pa.

Application September 27, 1932, Serial No. 635,111

6 Claims. (Cl. 238—292)

This invention relates to railroad base plates and fasteners, and has for its object the production of a simple and efficient railroad base plate which is provided with a lock for efficiently locking the rail in engagement with the base plate, at the same time assuring accuracy and security under all conditions.

Another object of this invention is the production of a simple and efficient rail base plate and fastener which may be efficiently and securely attached to a tie for the purpose of firmly attaching the rail against accidental displacement.

Another object of this invention is the production of a simple and efficient fastening means for rails in the nature of a base plate having a specially constructed wedge-shaped securing element which is so attached and supported as to permit of an efficient and accurate adjustment for the purpose of firmly securing a rail in place.

A further object of this invention is the production of a simple and efficient railroad base plate which is so constructed as to facilitate the placing of the rail in engagement with the base plate.

In the drawing:

Figure 1 is a side elevation of the improved railroad base plate, the rail being shown in vertical section and mounted upon the base plate;

Figure 2 is a top plan view of the structure shown in Figure 1, the rail being shown in longitudinal section through its web portion;

Figure 3 is an end elevation of the railroad base plate looking at the end of the base plate which is provided with the wedge-shaped clamp for locking the rail in position; and

Figure 4 is a section taken on line 4—4 of Figure 3.

By referring to the drawing, it will be seen that 1 designates the tie which may be of any suitable or desired structure, that is to say, of wood, metal, or plastic composition without departing from the spirit of the invention. Mounted upon the tie 1 is the base plate 2 which, if it is so desired, and for certain types of ties may be provided with spurs or anchoring means 3 upon the bottom thereof for firmly gripping into the upper face of the tie 1 and facilitating the anchoring of the base plate 2 against slipping. This particular structure is adapted for use in conjunction with wooden ties and certain plastic ties such as concrete and the like, if desired, and may or may not be used in conjunction with the present invention, depending upon the particular type of tie upon which the device

is adapted to be mounted. The base plate 2 may be fastened to the tie 1 by means of spikes or by means of the bolts 4 which bolts may be provided with suitable lock nuts 5 and locking washers 6 for constituting an efficient means for anchoring and locking the base plate 2 in position. The particular type of the means for anchoring the base plate upon the tie may be modified without departing from the spirit of the invention.

As shown in Figures 1 and 4, the base plate 2 is provided upon one side thereof with an overhanging lip 7, the base plate 2 being also provided with a downwardly curved socket 8 extending under the lip 7, for the purpose of permitting the base 9 of the rail 10 to be inserted under the lip 15 7 when placing the rail 10 in position. The base plate 2 is provided at its opposite end with respect to the lip 7 with a wedge-receiving housing 11 the inner edge 12 of which is adapted to snugly abut against the longitudinal edge 13 of the base 9 of 20 the rail 10. The downwardly curved socket 8 formed under the lip 7, as previously explained, will permit the rail 10 to be tipped sideways and allow the base 9 to extend under the lip 7 until the longitudinal edge 13 of the base 9 falls into 25 snug contact with the inner wall 12 of the wedge-receiving housing 11.

The wedge-receiving housing 11 is preferably of a rectangular structure having a flat bottom 14 and an enlarged wedge-receiving compartment 30 15 into which the wedge block 16 is adapted to be slidably mounted. The wedge block 16 is provided with an upper rear inclined face 17 and a forward tapering nose 18, which forward tapering nose 18 is adapted to project beyond the inner wall 12 of the housing 11 and overhang the upper face of the base 9 of the rail adjacent the longitudinal edge 13 thereof. The locking wedge block 16 is provided with a longitudinally extending groove 19 beyond the upper face thereof into 40 which is adapted to fit the lower end of the clamping screw 20. A binding screw 21 is carried by the housing 11 in the rear of the clamping screw 20, and this binding screw 21 is adapted to contact with the inclined face 17. When screwing the rail 10 in position, the screw 20 is slightly loosened and the wedge block 16 is forced into place as accurately as possible at which time the binding screw 21 is threaded downwardly through the housing 11 into intimate contact with the inclined face 17, thereby forcing the wedge clamping block 16 inwardly within the casting 11 and also causing the tapering nose 18 to be forced in wedging contact with the base 9 of the rail adjacent the longitudinal side edge 13. 55

The clamping screw 20 may then be adjusted to firmly fit within the groove 19 and assist in holding the wedge shaped block 16 in position. It will be seen that by means of this particular adjustment the block 16 will constitute a simple and efficient reinforcing means for holding the rail 10 in position and extraordinary pressure must be brought against the rail through the wedging clamping action previously described. Suitable spring washers may be used in connection with the screws 20 and 21 to permit of proper adjustment and the locking of these screws against removal.

A web bracing arm 22 is carried by the top of the housing 11, as shown in the drawing and this web bracing arm has its inner end 23 contacting with the web 24 of the rail 10. The arm 22 extends at an angle of approximately 45 degrees to the plane of the rail base. This rail bracing arm 22 is provided with a shoulder 25 which is adapted to contact with the inner face of the housing 11. The arm 22 is provided with a projecting tongue 26 which is engaged by the screw 20, as shown, for the purpose of anchoring the arm 22 in position.

From the foregoing, it will be seen that a very simple and efficient fastener has been provided which may be especially useful on curves and other locations within the length of the track where an extraordinary bracing and anchoring means is advisable and necessary. It should be understood that the device may be duplicated at spaced intervals along the length of the track and that it is not necessary, under ordinary conditions, that the rail be fastened to the tie in every instance by means of this particular type of fastener in view of the fact that only a few may be found necessary to accomplish the desired results at specified intervals throughout the length of the track.

It should be understood that certain detail changes in the mechanical construction, combination and arrangement of parts may be employed without departing from the spirit of the invention, so long as these changes fall within the scope of the appended claims.

Having described the invention, what is claimed as new is:

1. A device of the class described comprising a base plate adapted to support a rail, a housing carried by said base plate, a wedge block slidably mounted within said housing adapted to engage the base of a rail, said wedge block being provided with an upper inclined rear end, and a clamping screw carried by said housing and engaging said inclined face of said wedge block for permitting the longitudinal wedging adjustment of said wedge block within said housing for forcing the same into locking position with the base of a rail.

2. A device of the class described comprising a base plate adapted to support a rail, a housing carried by said base plate, a wedge block slidably mounted within said housing and provided with an upper inclined rear end, a clamping screw carried by said housing and engaging said inclined face of said wedge block for permitting the longitudinal wedging adjustment of said wedge block within said housing for forcing the same into locking position with the base of a rail, and said wedge block having an elongated tapering

nose adapted to overhang the base of a rail for locking the rail against overturning or vertical movement with respect to said base plate.

3. A device of the class described comprising a base plate adapted to support a rail and brace the rail against overturning or vertical movement with respect to said base plate, a housing carried by said base plate, a wedge block slidably mounted within said housing and provided with an upper inclined rear end, a clamping screw carried by said housing and engaging said inclined face of said wedge block for permitting the longitudinal wedging adjustment of said wedge block within said housing for forcing the same into locking position with the base of a rail, said wedge block having an elongated tapering nose adapted to overhang the base of a rail for locking the rail in position, and said wedge block having a longitudinally extending groove upon its upper face and a clamping screw carried by said housing and engaging said groove for binding said wedge block in position.

4. A device of the class described comprising a base plate adapted to support a rail, means for securing the base of a rail thereto, a web bracing arm adapted to extend at an angle of substantially forty-five degrees to said base plate and to contact with the web of a rail for holding a rail against overturning movement, said arm provided with a shoulder, a ledge formed upon said base plate for receiving said shoulder, a projecting tongue fitting upon said base plate adapted to engage the base of a rail for holding a rail supported thereby against vertical movement, and means for locking said projecting tongue in position.

5. A device of the class described comprising a base plate adapted to support a rail, means for attaching a rail thereto, a housing carried by said base plate, adjustable clamping means carried by said housing for engaging the base of a rail and adapted to hold a rail supported thereby against vertical movement, a bracing arm adapted to engage the web of a rail for holding a rail supported by the base plate against overturning movement and having a depending shoulder adapted to overhang the inner edge of said housing, a securing tongue fitting upon the top of said housing, and a clamping screw passing through said tongue and acting as a common means for anchoring said tongue and adjustable rail engaging means in position.

6. A rail supporting and clamping device comprising a base plate adapted to support a rail, means for engaging one side of the base of a rail to hold the rail against vertical movement, an individually adjustable means carried by said base plate and adapted to engage the web of a rail upon the side opposite to the first mentioned means for bracing the rail and holding the same against overturning movement, and means individually adjustable upon said base plate for engaging the base of a rail and located on the same side of the rail as said brace and providing means for holding the base of the rail firmly upon said base plate and also maintaining a firm contact between the web of the rail and said brace.

WESLEY E. WENNER. 70
